UNITED STATES PATENT OFFICE

CLAUDE HADFIELD, OF PHILADELPHIA, PENNSYLVANIA

WELT BAR

Application filed April 27, 1929. Serial No. 358,519.

This invention relates to welt bars for use with flat knitting machines which are adapted for the knitting of full fashioned hosiery.

The object of the invention is to produce a 5 welt bar which will facilitate the welt-turning operation. The construction and operation of a welt bar made in accordance with the principles of my invention will be fully disclosed hereinafter, reference being had to 10 the accompanying drawings, of which:

Fig. 1 is a diagrammatic sectional elevation through the welt bar, and showing a web of knitted fabric stretched between the hooks of the welt bar and the needles of a 15 flat knitting machine;

Fig. 2 is a view similar to Fig. 1, but showing the welt bar in the welt-turning position, with respect to the needles of the machine;

Fig. 3 is a view similar to Fig. 2, drawn to 20 an enlarged scale;

Fig. 4 is a perspective view of one of my improved welt bar hooks;

Fig. 5 is a transverse sectional view taken on the line 5—5, Fig. 4; and

Fig. 6 is a transverse sectional view taken on the line 6—6, Fig. 4.

Welt bars of the prior art consist of a plurality of plain hooks spaced apart in accordance with the gage of the machine in which 30 the bar is adapted to be used, the shanks of the hooks being respectively provided with grooves in their rear faces, the said shanks being secured between a pair of substantially similar bars adapted to be secured together 35 by suitable screws for clamping the hooks in place.

As is well known in the art, the welt-turning operation is more difficult, and requires greater skill and experience on the part of the knitter, than any other operation in the 40 knitting process. Even with the most skilled knitter, some of the needles of the machine will become bent or broken during the welt-turning operation, due to the fact that 45 the said needles are necessarily subjected to lateral strains incidental to that part of the operation wherein the welt bar hooks are being removed from the stitches of the knitted fabric, which previously have been 50 pressed down on the hooks and the needles,

after the hooks have been properly aligned with the needles.

In using a welt bar made in accordance with the principles of my invention, it is not necessary to place any lateral strain 55 whatsoever on the needles during any part of the welt-turning operation, therefore, the possibilities of bent or broken needles is obviated. Furthermore, with the use of my improved welt bar the necessary steps of the 60 operation are reduced to a minimum, as will be fully disclosed hereinafter.

Referring to the drawings, my improved welt bar is indicated, generally, at A, the needles of the machine being indicated at B, 65 and the knitted fabric indicated at C.

The welt bar A consists of a base bar 1 and a clamp bar 2 rigidly secured together by means of screws 3. The base bar 1 is grooved as indicated at 4 for the reception of 70 the shanks 5 of the welt bar hooks 10. The base bar 1 is also provided with a series of apertures 6 for the reception of butts 7 formed on one end of each of the welt hooks 10.

As shown in Fig. 3, the shanks 5 of the 75 hooks 10 project beyond the surface 8 of the base bar 1 and are engaged by the surface 9 of the clamp bar 2 adjacent one longitudinal edge thereof, the opposite longitudinal edge of the clamp bar being provided with a rib 11 80 which bears against the surface 8 of the base bar 1 and acts as a fulcrum for the clamp bar 2, so that when the screws 3 are turned down tightly the shanks 5 of the hooks 10 will be rigidly secured within the welt bar 85 A between the parts 1 and 2 thereof.

A portion 12 of the shank 5 of each of the 90 welt bar hooks 10 extends beyond one longitudinal edge of the welt bar A and at its outermost end is provided with a suitable crook 13.

Pivots mounted at 14 in the projecting shank portion 12 of the hook 10 is a latch 15, which is adapted, under certain predetermined conditions, to swing about its pivot 95 to either of the positions shown in Figs. 1 and 2, respectively.

As shown in Fig. 3, the latch 15 is provided with a flat thin blade portion 16 located within a slot 17 formed in the shank portion 100

12 of the hook 10. The said latch is also provided at its outer end with an enlarged portion 18, cupped as indicated at 19, for the purpose of engaging and covering the point 20 of the hook 10.

5 The upper end of the slot 17 connects with a groove 21 formed in the rear face of the shank portion 12 and adapted to receive the beard 22 of one of the needles B, as clearly shown in Fig. 3.

10 In operation the welt bar is positioned in the machine in the usual manner at the start of the knitting operation, with the crooks 13 of the hooks 10 projecting between the needles B of the machine, and the latches 15 thrown back into position shown in Fig. 1.

15 The knitting operation then progresses in the usual manner until sufficient of the fabric C has been knitted to produce the turned welt 20 of the stocking, after which the welt bar is moved from the position shown in Fig. 1 to the position shown in Figs. 2 and 3.

20 During this movement, from the one position to the other, the stitches α held in the crooks 13 are moved along the shanks of the hooks 10 and the latches 15 until they lie intermediate the cupped ends 18 of the latches and the adjacent longitudinal edge of the welt bar, or in other words until the 25 stitches are behind the latches on the shanks of the hooks.

25 The welt bar is then placed in the welt-turning position shown in Figs. 2 and 3 with the beards 22 of the needles B lying within the grooves 21 of the shank portions 12 of the welt hooks 10 and the ends 23 of the needles B lying in a longitudinally extending groove 24 formed in the edge of the base bar 1 immediately adjacent the welt hooks 10, it being noted that the stitches α which 30 are held on the needles B occupy a position substantially below the ends 13 of the welt hooks 10.

35 With the welt bar in this position with respect to the needles the transfer of the stitches α from the welt hooks 10 to the needles B is accomplished in the simplest sort of way, i. e. by merely passing the finger along the web of fabric and exerting a downward force thereon, the stitches α being 40 thereby moved longitudinally of the hooks 10 and under the cupped ends 18 of the latches 15, continued downward movement of the fabric effecting the swinging of the latch 45 es from the position shown in Fig. 1 to the position shown in Figs. 2 and 3, wherein the said cupped ends 18 of the latches completely 50 cover the points 20 of the welt hooks 10, and permit the said stitches α to be moved, without 55 interruption, over the said latches and off the end of the said welt hooks onto the shanks 60 of the needles B, thus completing the welt turning operation.

65 The welt bar A is then free to be raised from the needles B without necessitating any

lateral or other strains being placed upon the needles of the knitting machine or the hooks of the welt bar.

During the welt-turning operation, the usual bar or wire D is placed in the loop 70 formed in the fabric C, and this bar is then connected to the usual take-up mechanism of the knitting machine and the knitting progresses in the same usual manner, after the welt bar A has been removed from the 75 needles B.

I claim:

1. A welt bar, for use in flat knitting machines, comprising a plurality of hooks adapted to be respectively aligned with the 80 needles of the said machine, and a relatively movable element on each hook adapted to cover the point thereof when the hooks are aligned with the needles, said bar having a socket at the base of each hook to receive the 85 point of the needle with which the hook is aligned.

2. A welt bar, for use in flat knitting machines, comprising a plurality of hooks adapted to be respectively aligned with the 90 needles of the said machine, and a latch pivotally mounted on each hook and adapted to be swung on its pivot to a position wherein a portion of the latch covers the point of the hook with which it is associated when the hooks are aligned with the needles, said 95 bar having a socket at the base of each hook to receive the point of the needle with which the hook is aligned.

3. A welt bar, for use in flat knitting machines, comprising a plurality of hooks adapted to be respectively aligned with the needles of the said machine, each hook comprising a shank having a groove adapted to receive a portion of the needle with which it is aligned, and a latch pivotally mounted on each hook and adapted to be swung on its pivot to a position wherein a portion of the latch covers the point of the hook with which it is associated when the hooks are aligned with the needles, said bar having a socket located at the base of each hook in alignment with the groove formed in the shank of the hook, to receive the point of the needle and to function as a stop between the hook and the needle aligned therewith.

CLAUDE HADFIELD.
